CLAIM

The ornamental design for a fish filleting glove, as shown and described.

DESCRIPTION

FIG. 1 is a palm plan view of a fish filleting glove showing our new design that includes a serrated section that protrudes through a slit located on the outer side of the glove's index finger and a single spike that protrudes through a slit centered on the inner side of the glove's thumb;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is an enlarged front elevational view of the serrated section that extends upward from the upper surface of a ring that is inserted into the glove's index finger;

FIG. 8 is an enlarged top plan view thereof;

FIG. 9 is an enlarged bottom plan view thereof;

FIG. 10 is an enlarged right side elevational view thereof;

FIG. 11 is an enlarged left side elevational view thereof;

FIG. 12 is an enlarged front elevational view of the single spike that extends upward from the upper surface of a ring that is inserted into the glove's thumb;

FIG. 13 is an enlarged top plan view thereof;

FIG. 14 is an enlarged bottom plan view thereof;

FIG. 15 is an enlarged right side elevational view thereof; and, FIG. 16 is an enlarged left side elevational view.

For ease of illustration the serrated and spike rings are shown separately from the glove in FIGS. 7–16.
